CLAIM

The ornamental design for a lip product container, as shown and described.

DESCRIPTION

FIG. 1 is a front perspective view of a lip product container in an open configuration showing our design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken lines adjacent to shaded areas represent unclaimed boundaries of the claimed design and form no part of the claimed design. All other broken lines show unclaimed portions of the lip product container that form no part of the claimed design.

The different stippled textures represent changes in material.
